UNITED STATES PATENT OFFICE.

CARL H. BISSELL, OF SYRACUSE, NEW YORK, ASSIGNOR TO CROUSE-HINDS COMPANY, OF SYRACUSE, NEW YORK, A CORPORATION OF NEW YORK.

SERVICE ENTRANCE CAP.

Application filed August 29, 1916. Serial No. 117,433.

To all whom it may concern:

Be it known that I, CARL H. BISSELL, a citizen of the United States, and a resident of Syracuse, in the county of Onondaga and State of New York, have invented a certain new and useful Service Entrance Cap, of which the following is a specification.

This invention has for its object a box for use in connection with electric conduits, and what is called for convenience, a service entrance cap, as it is mounted upon the upper end of a conduit through which the service wires are led into a building or other structure, which service entrance cap is simple in construction and highly efficient and durable in use. The invention consists in the novel features of construction hereinafter set forth and claimed.

In describing this invention, reference is had to the accompanying drawings in which like characters designate corresponding parts in all the views.

Figure 1 is an elevation of a preferable form of my service entrance cap, the contiguous portion of an electrical conduit being also shown.

Figures 2 and 3 are inner face views of the top section and the lower section of the cap, with nipple attached thereto.

Figure 4 is a vertical section view of parts seen in Fig. 1.

This cap consists generally of upper and lower sections separable along a plane extending generally, in a horizontal direction and confining wire passages between them, the lower section being provided with means for connection with the conduit, and means for holding the sections from separation.

1 and 2 designate the upper and lower sections which are usually formed of an insulating compound, the upper section having a rounding top surface for facilitating the shedding of water, this top surface merging into a peripheral vertical cylindrical surface 3 at the rear of the cap. The section 1 is in the form of an overhang or hood at 4 at its front end, the sections 1 and 2 having an under surface 5 at their front ends.

The section 1 is formed with a shallow recess 6 and with grooves 7 in its lower face, the grooves leading from the recess 6 and opening through the under surface 5; and the lower section 2 is formed with a hub or annular flange 8 extending into the recess 6 and fitting the side walls 9 thereof, and with

grooves 10 complementary to the grooves 7 and therewith forming wire holes.

The lower section is also formed with a bearing face 11 around the hub 8, and on which rests the flat surface 12 of the section 1 around the recess 6 and between grooves 7. The lower section 2 is also provided with a vertical passage 13 arranged concentric with the hub 8.

14 is a metallic nipple, the body of which fits into a counter bore at the lower end of the passage 13, said nipple being internally threaded for receiving the threaded end of an electrical conduit 15.

The means for holding the sections 1, 2 from separation, comprises means which coact with the top section 1 and the nipple 14 to clamp said section 1, and nipple on the upper and lower sides of the section 2. As here illustrated, said section 1 and the nipple 14 are clamped together by screws 16 extending vertically through laterally extending ears 17, 18 provided on the section 1 and the nipple 14, these screws 16 being independent of the section 2 and located outside of the periphery of the section 2.

In operation, the nipple 14 is first screwed into the top of a pipe and the wires passed through the passage 13 of the section 2 and into the pipe whereupon the section 2 can be placed on the nipple and finally the top section 1 placed in position and the parts clamped together by the screws 16.

Owing to the fact that the sections 1, 2 separate along a horizontally extending plane, the wires can be easily manipulated in the pipe and further owing to such separation of the sections 1, 2 and to the boss 8 fitting into the recess 6, and to the bearing surfaces 11, 12 and to the arrangement of the wire holes, the cap is water tight.

What I claim is:

1. A service entrance cap comprising an upper cap section, a lower section formed with a vertical passage therethrough, an attaching nipple below the lower section and separable therefrom, and means for clamping the top section toward the nipple, said means being independent of the second mentioned section, substantially as and for the purpose specified.

2. A service entrance cap comprising upper and lower sections separable along a plane extending in a general horizontal direction, and confining a wire space and pas-

sages between them, said passages extending downwardly toward their outer ends, and opening through an under outer face of the cap, the lower section being formed with a 5 vertical passage, a nipple extending into the lower end of the passage, and being provided with means for connection with a conduit, the top section and the nipple being provided with laterally extending ears project-

ing beyond the outer surface of the lower section, and clamping members extending through said ears, substantially as and for the purpose set forth.

In testimony whereof, I have hereunto signed my name, at Syracuse, in the county 15 of Onondaga, and State of New York, this 5th day of June 1916.

CARL H. BISSELL
